(57) **CLAIM**

The ornamental design for a probe for an ultrasonic diagnosis apparatus, as shown and described.

DESCRIPTION

FIG. 1 is a front, bottom and right side perspective view of a probe for an ultrasonic diagnosis apparatus, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken line showing of the remainder of the probe for an ultrasonic diagnosis apparatus is for illustrative purposes only and forms no part of the claimed design.
